UNITED STATES PATENT OFFICE.

GUY N. EVANS, OF GRINNELL, IOWA.

LEAF-TURNER.

1,266,437.

Specification of Letters Patent. Patented May 14, 1918.

Application filed November 14, 1916. Serial No. 131,275.

To all whom it may concern:

Be it known that I, GUY N. EVANS, a citizen of the United States, and resident of Grinnell, in the county of Poweshiek and 5 State of Iowa, have invented certain new and useful Improvements in Leaf-Turners, of which the following is a specification.

The present invention relates to changeable exhibitors and has particular reference 10 to new and useful improvements in leaf turners.

An object of my invention is to provide a leaf turner having an improved arrangement of exhibiting mechanism which is simple 15 in construction, effective in operation and strong and durable.

Another object of my invention is to provide a novel and improved form of carriage for supporting the leaf frame, and an im- 20 proved mechanism for intermittently imparting rotative movement to the carriage.

A further object of my invention is to provide a leaf turner adapted to exhibit for instance a plurality of sheets of music suc- 25 cessively without a complicated motion transmitting mechanism and provide a device which will accurately move one sheet holding frame at a time to exhibit both sides of a sheet of music.

30 Other objects and advantages of my improved leaf turner not hereinbefore set forth will appear from the following detailed description and the claims, taken with an inspection of the accompanying drawings, in 35 which:

Figure 1 is a front elevational view of a leaf turner embodying the improvements of my invention;

Fig. 2 is a side elevational view of the 40 same;

Fig. 3 is a top plan view of the shifting mechanism;

Fig. 4 is an enlarged fragmental detail 45 view of the frame oscillating member; and

Fig. 5 is a similar view of the carriage for supporting the leaf holding frame.

Referring more particularly to the drawings, wherein similar characters of reference designate like and corresponding parts 50 throughout the various views, 10 designates the base of my improved leaf turner, the same having a rear standard 11 extending upwardly therefrom, said standard 11 hav- 55 ing a top laterally extending portion 12 for a purpose which will hereinafter appear.

A carriage designated C in its entirety is

rotatably mounted between the top portion 12 and the base 10, said carriage comprising a drum portion 13 carried in bearing brackets 14 and 15, a top holding plate 16 and a bottom holding plate 17, the latter having the peripheral edge thereof formed with a plurality of ratchet teeth 18. A bearing shaft 19 extends from the base to the top portion of the main supporting frame, said shaft 60 65 acting as a rotative support for the drum 13. The bearings 14 and 15 carry a vertically disposed rod 20 for a purpose which will hereinafter appear.

The sheets to be exhibited are placed in 70 frames F, one of which is best shown in Fig. 4. Referring to Fig. 4 I provide a frame composed of side portions 21 connected at the outer edges as at 22, the portions of the frame being open to permit insertion of 75 a sheet of music. When desired transparencies 23 may be carried by the side portions 21 of the frame so that the sheets may be visible therethrough. The inner end of the frame is connected to a shaft 24, the free 80 ends of which are engaged rotatively with the plates 16 and 17. The sections of the frame are hingedly connected together on the shaft 24, the connection 22 being of a detachable character permitting opening of 85 the frame.

A tubular member 25 encircles one portion of the frame F, the outer surface of said tubular member having a pair of ribs in spaced relation thereon, said ribs being 90 adapted to engage, at times, said bar 20, whereby to oscillate the sheet carrying frame.

To partially rotate the carriage C inter- 95 mittently I provide a pair of levers 28 and 29 pivotally arranged on the shaft 19 beneath the base plate 17 of said carriage. An arm 30 is pivotally mounted on the lower end of the shaft 19 and projects radially of the plate 17, said arm carrying a pair of 100 curved pawls 31 and 32 on its free end, said pawls being pivoted together and to said arm as at 33. The ends of the pawls 31 and 32 are directed inwardly to engage the teeth 18. A pair of links 34 and 35 extend be- 105 tween the levers 28 and 29 and the pawls 31 and 32, respectively. A pair of slid- 110 able rods 36 and 37 serve to impart movement to the levers 28 and 29 to engage said pawls with the teeth and to impart rotative move- 115 ment to the carriage C. Handles 38 are carried by the free ends of the rods 36 and 37.

The arm 30 is provided with a pair of enlargements 40 and 41 carrying pins 42 to be engaged by the levers 28 and 29, so that when one of the levers is moved its movement will be imparted to the arm 30, there being, of course, slight relative movement between the levers 28 and 29 and said arm 30 before said pins begin to act, so that movement of the levers will first engage the pawls 44 with the plate 17 and continued movement of the levers will cause the arm 30 to shift, moving the plate 17 through a partial rotation.

A pawl member 43 carried by a spring 44 serves to engage the teeth normally and maintain the carriage in the position to which the same has been moved.

In operation motion is imparted to one of the levers 28 or 29 by means of the handles 30. The lever moved, will first by virtue of its connecting link, move one of the pawls into engagement with the teeth of the plate 17. Continued movement of the lever will bring the same into engagement with one of the pins carried by the arm 30 actuating said arm and causing the same to move through an arc of a circle, this movement being transmitted to the plate 17. When the carriage C is moved through a partial rotation, the inner edge of one of the sheet carrying frames will engage the bar 20, said frames being oscillated to exhibit one side of a sheet of music. When all of the sheets have been exhibited the opposite lever to the one first actuated may be moved to return the sheet to normal position. This will also be found useful in the event that it is necessary for instance to play one sheet of music twice. Any number of sheets may be employed by increasing the number of holding frames F. Of course, I do not limit my invention to any specified use, in view of the fact that the operating mechanism and arrangement of frames may be altered for adaptation to any use to which changeable exhibitors are usually put.

The part 43 would not prevent rotation of the plate 17, as this part 43 is a spring pressed pawl, that is so associated with the toothed edge of the plates, that upon rotation of said plates by the operation of the pawls and levers, this part will be forced outwardly, to allow said base to move, and when the base or plate 17 has reached the desired position, the pawl 43 will once more cooperatively engage the same to lock it normally in that position.

From the above description taken in connection with the accompanying drawings, it is thought that a clear and comprehensive understanding of the construction, operation and advantages of my invention may be had, and while I have shown and described the device as embodying a specific structure,

I desire that it be understood that such changes may be made in such structure as do not depart from the spirit and scope of the invention as claimed.

Having thus fully described my invention, what I claim as new and desire to secure by Letters Patent, is:—

1. In a leaf turner, the combination of a base having a standard, a carriage rotatable on said base, a plurality of sheet holding frames oscillatable in said carriage, means on the base to engage said frames to shift the same when the carriage is partially rotated, said carriage having a toothed base portion, a plurality of pawls intermittently and alternatively engageable with said toothed base, and a plurality of oppositely arranged lever members to intermittently and alternatively actuate said pawl members.

2. In a leaf turner, the combination of a base having a standard, a carriage rotatable on said base, a plurality of sheet holding frames oscillatable in said carriage, means on the base to engage said frames to shift the same when the carriage is partially rotated, a pair of lever members oppositely arranged and mounted on said base beneath said carriage, said carriage having a base portion provided with peripherally arranged sheets, an arm, a pair of pawl members carried by the free end thereof, said pawl members being adapted to engage the toothed periphery of said carriage base, a pair of levers, link members connecting said levers with said pawls, means to connect said levers with said arms to shift the same, said levers being adapted for actuation whereby to intermittently actuate the pawl members to partially rotate said carriage and exhibit the opposite sides of sheet members carried in said frames.

3. In a leaf turner, the combination of a base having a standard, a carriage rotatable on said base, a plurality of sheet holding frames oscillatable in said carriage, means on the base to engage said frames to shift the same when the carriage is partially rotated, an arm pivotally mounted on said base and having a pair of pivotally mounted pawl members on the free end thereof, the base of said carriage being provided with peripheral ratchet teeth to be engaged by said pawls, a pair of levers, link members connecting said levers with said pawls, a pair of rod members connected with the free ends of said levers to actuate the same, and means to maintain said carriage in a position to which the same is shifted, said pawl members being actuatable by said levers to engage with said teeth and impart movement to said carriage.

4. In a leaf turner, the combination of a base having a standard, a carriage rotatable

on said base, a plurality of sheet holding frames oscillatable in said carriage, means on the base to engage said frames to shift the same when the carriage is partially rotated, said carriage having a toothed base portion, a plurality of pawls intermittently and alternatively engageable with said toothed base, a plurality of oppositely ar-

ranged levers to intermittently and alternatively actuate said pawls, and a spring 10 pressed pawl engageable with the toothed base portion to normally lock said carriage.

In testimony whereof, I affix my signature hereto.

GUY N. EVANS.
